CLAIM

The ornamental design for a diaper cover, as shown and described.

DESCRIPTION

FIG. 1 is a front perspective view of a diaper cover, showing our new design in a folded position;
FIG. 2 is a front elevational view thereof;
FIG. 3 is a side elevational view thereof, the opposite side elevational view being identical thereto;
FIG. 4 is a back elevational view thereof;
FIG. 5 is a top elevational view thereof;
FIG. 6 is a bottom elevational view thereof; and,
FIG. 7 is an elevational view thereof in the unfolded position.

FIG.1

FIG.2
